UNITED STATES PATENT OFFICE.

RUFUS WAPLES, OF WAYNE, PENNSYLVANIA.

MEANS FOR SECURING RAILROAD-RAILS TO ROAD-BEDS.

1,260,736.

Specification of Letters Patent. Patented Mar. 26, 1918.

Application filed August 6, 1917. Serial No. 184,645.

To all whom it may concern:

Be it known that I, RUFUS WAPLES, a citizen of the United States, residing in Wayne, Delaware county, Pennsylvania, have invented certain Improvements in Means for Securing Railroad-Rails to Road-Beds, of which the following is a specification.

My invention relates to certain improvements in the means for securing rails in 10 position on a roadbed.

One object of the invention is to provide means for securing the rails directly to the ballast or the permanent bed of the railroad.

A further object of the invention is to 15 provide means for vertically adjusting the rails by wedges located on the ballast and which support the rails.

A still further object of the invention is to provide adjustable means for securing the 20 rails to the ballast without disturbing the ballast.

In railways of the present construction, the weight of the rolling stock consolidates and solidifies the roadbed, and when ties are 25 used constant tamping is required which disturbs the bed. My improved construction allows for the adjustment of the rails to gage or grade without disturbing the ballast or road bed and thus the ballast forms a 30 firm anchorage and supporting bed for the wedge-shaped blocks, which carry the rails, and these blocks may be driven up in surfacing the track without disturbing the ballast.

By the use of my improvement, the supporting blocks or wedges may be placed 35 comparatively close together, as it is unnecessary to tamp the bed under the blocks, as has heretofore been deemed necessary in the use of ties.

40 The universal practice of tamping under the cross ties is now considered objectionable, in that many of the ballast units are turned on edge or broken into small fragments and the movement of the rails, due 45 to the use of the present heavy equipment, turns these units to a horizontal position, giving space to play, which grows until the tamping must be repeated.

In the accompanying drawings:

50 Figure 1 is a plan view of sufficient of a railroad bed to illustrate my invention;

Fig. 2 is a transverse sectional view on the line 2—2, Fig. 1;

55 Fig. 3 is a transverse sectional view on the line 3—3, Fig. 1;

Fig. 4 is a detached perspective view illustrating one of the anchor plates;

Fig. 5 is a detached perspective view of one of the angular coupling members;

Fig. 6 is an enlarged sectional view showing the insulated joint;

Fig. 7 is a plan view illustrating a modification of the invention;

Fig. 8 is a transverse sectional view on the line 8—8, Fig. 7;

Fig. 9 is a view of a modification of the means for securing the rod and bar together; and

Fig. 10 is a modification of the construction shown in Fig. 7.

Referring to the drawings, 1 is the foundation made of ordinary earth properly graded. 2 is the roadbed, which, in the present instance, consists of a compact mass of broken stone, as shown. These stones 70 are preferably trap rock and the edges are sharp so that they will be compacted by the running of trains and will hold together as a mass, resisting the weight and pressure of the cars passing over the tracks, as by 75 the use of my invention they will never be loosened and tamped to support the track. Where stone is not available, clay, properly compacted, may be used with or without 80 stone slabs or iron plates.

3, 3 are the rails spaced a given distance apart and located under these rails are the wedges 4 and between the upper surface of the wedges and the rails are metallic plates 5, which are preferably spiked to the wedges 90 after adjustment. The upper surface of the ballast is preferably horizontal at the center x and inclined at each side y , forming an inclined bed for the wedges 4, the upper surfaces of the wedges being horizontal. The 95 wedges are preferably rounded at the narrow end so that they can be forced over the surface of the ballast when it is desired to raise either rail. While the upper inclined surface of the ballast may consist of compacted stone, I preferably lay a surface of asphalt, or other suitable material, which will form a comparatively smooth bed at this portion of the ballast and this material also acts as a waterproof surface so as to prevent 100 rain water from entering the ballast to an appreciable extent. While this material may only extend over the inclined surface of the ballast, in some instances, it may be continued over the horizontal portion where 110

a roadbed that is absolutely waterproof is desired. It is well understood that if water be kept from the permanent bed 1, there is little trouble in keeping the foundation in 5 proper condition.

Embedded in the ballast is a bar 6. This bar has a horizontal portion 7 and two slightly curved portions 8 and secured to the ends of the bar are anchors 9, the bars 10 being turned up at 10 to rest back of the anchors. These anchors may be fastened to the bars in many different ways. The bars are bent, as at 10^a, in the form of a curve, in the present instance, and there is an anchor 11 at one end of the curve and an angular coupling member 12 at the opposite end of the curve. The bar extends through a hole 13 in this member, as clearly shown in Fig. 2. The anchors are located sufficiently below the upper surface of the ballast so that any lateral strains on the bed will be resisted by the ballast. Furthermore, it will be noticed that the anchors are located under the wedges so that when a 25 train is passing over the tracks, which is the only time that the bar is subjected to strains, the weight of the train will keep the anchors in place.

The angular coupling members, as shown 30 in the drawings, are located at each end of the horizontal portion 7 of the bar 6 and between the rails 3. These coupling members take the strain of the outward thrust on the rails and are made sufficiently strong 35 to resist this strain. In the present instance, they may have side ribs 14, as clearly shown in Fig. 5. The bolts 15 extend from the coupling members to the outer flanges of the rails. These bolts are hooked at 16 so as to 40 engage these flanges and where it is desired to insulate the joint between the rod and the coupling, I provide an insulating sleeve 17 which extends through the opening 18 and is flanged, as shown, so as to form a bearing 45 for the nuts 19, which are on the threaded portion of the hooked bolt 15. By turning these nuts in one direction the rail 3 can be moved toward the center of the track and by turning the nuts in the opposite direction 50 the rail is allowed to be moved outward. The greatest side strain placed on the rail is the strain outward, especially when the train passes around curves. These bolts 15 are of sufficient strength to resist these 55 strains. The bolts have a loose fit in the openings in the angular couplings to allow for adjustments.

In order to hold the inner flange of the rail down to its seat, I provide additional 60 anchors consisting of an inclined rod 20 having an anchor 21 at its outer end embedded in the ballast, and, in the present instance, turned at an angle at 22 and perforated for the passage of a short adjusting

rod 23 having a hook 24 at its upper end 65 which engages a base flange of the rail. The opposite end of this rod 23 is threaded to receive the nuts 25. These nuts, in the present instance, are located above the upper surface of the ballast so that when the gage 70 of the track needs to be altered the nuts on both the bolts and rods can be adjusted without interfering with the ballast.

When it is necessary to raise either one of the rails, all that is necessary is to draw 75 the spikes that secure the plates 5 to the wedges 4 and then drive the wedges until the rail is at the height desired. Then the spikes are driven again so as to secure the plates to the wedges. It will be noticed 80 that the plates have ribs at each side which engage the base flange of the rail and hold the plate and the wedge against longitudinal movement.

When the wedge has been driven up its 85 length and further hard service causes subsidence of the ballast, the wedge is withdrawn and a small amount of broken stone is thrown on the bed of the wedge and the latter is replaced and secured.

It will be seen by the above construction that I entirely dispense with what is known as a "cross tie" to which both rails are rigidly secured, and I substitute for this tie a substantial bar having anchors at both 95 sides, which is embedded in the ballast and which is attached independently to the two rails.

In some instances, the rods 20 may be attached to the same anchors as the bar 6, 100 but, in the main views of the drawings, I have illustrated independent anchors.

In Figs. 7 and 8, I have illustrated a modification in which lengths of a central T-shaped bar 26 extend throughout the 105 length of the track, midway between the rails 3, and the anchor bars 6^a are secured to this bar and the T-bar becomes the equivalent of the coupling member 12, shown in Figs. 1 and 2. Hook bolts 15^a connect this 110 T-bar 26 with the rails, as clearly shown in Figs. 7 and 8. In this instance, there are two longitudinal anchor plates 9^a extending one on each side of the track and embedded in the ballast, and the rods 6^a are secured to 115 these anchors. The rods 20^a are also secured to the anchors.

In some instances, instead of using the construction illustrated in Fig. 6, a construction such as shown in Fig. 9 may be 120 used, in which the coupling member 12^b is made of two bent pieces, one shaped to conform to the bolt 15^b and the other shaped to conform to the bar 16^b. The two pieces are secured together by a bolt 27.

In some of the claims, I have used the term "ballast", meaning the ordinary stone ballast consisting of a compacted mass of

broken stone or compacted clay and like material, which is distinguished from the ordinary separate ties or stringers of concrete.

5. In Fig. 10, I have shown a bar 6^b extending from the T-bar 26^a to an anchor 9^b and the rods 20^b are attached to the bar 6^b some distance from the anchor.

In some of the claims, I have used the 10 term "anchor" in its broad sense to include the transverse bars and anchor plates, or their equivalents.

I claim:

1. The combination in a railway structure, 15 of a ballast; anchors located in the ballast; supports for the rails mounted on the ballast; and means connecting the anchors with the rails.

2. The combination of a ballast; rails supported by the ballast; a series of anchors extending transversely within the ballast and under the rails; and means for attaching the rails to the anchors.

3. The combination of a ballast; a rail 25 supported by the ballast; transverse bars embedded in the ballast and having anchor plates thereon; and means for connecting the rails with the anchor plates.

4. The combination in a ballast, of rails; 30 means for supporting the rails on the ballast; a series of bars transversely arranged within the ballast and having anchor plates thereon; and means for engaging the outer flanges of the rails and secured to each bar.

35 5. The combination of a ballast; rails mounted on the ballast; a series of transverse bars embedded in the ballast and having anchor plates attached thereto and also embedded in the ballast; rods engaging the 40 outer base flange of each rail and independently and adjustably secured to the bars so that the gage of the track can be regulated without disturbing the ballast.

6. The combination of a ballast; rails 45 thereon supported by the ballast; a series of transverse bars embedded in the ballast and having anchors thereon; rods engaging the outer base flange of each rail and secured to each bar; and diagonally arranged 50 anchor rods embedded in the ballast and engaging the inner base flange of the rails.

7. The combination of a ballast; wedges 55 mounted on the ballast; rails supported by the wedges; anchors located in the ballast; and means connecting the anchors to the rails.

8. The combination of a ballast having oppositely inclined surfaces; wedges mounted on these inclined surfaces; rails supported 60 by the wedges; and anchors located in the ballast and secured to the rails independently of the wedges.

9. The combination of a ballast having an inclined surface at each side; wedges mount-

ed on the ballast; plates mounted on the 65 wedges and detachably secured thereto; rails supported by the plates; a series of transverse bars having anchor plates at each end; said anchor plates being located in the ballast under the wedges; and means for attaching the rails to the bars.

10. The combination of a ballast having an inclined surface at each side; a series of wedges mounted on each surface of the ballast; rails supported by the wedges and a 75 series of transverse bars; anchors on said bars, one set of anchors being at each end of each bar, the other set of anchors being on the bars within the space between the rails; and means for independently connecting the rails with the bars.

11. The combination of a ballast having an inclined surface at each side; a series of wedges mounted on each surface; rails mounted on the wedges; a series of transversely arranged bars mounted in the ballast, the center portion of the bars being nearer the surface of the ballast than the outer portions; anchor plates on the end portions of the bars; coupling members on 80 the center portion of each bar; and rods mounted in the coupling member and engaging the outer base flanges of the rails.

12. The combination of a ballast having an inclined surface at each side; wedges 95 mounted on the inclined portions of the ballast; rails mounted on the wedges; a series of transverse anchor bars embedded in the ballast; said bars being nearer the surface at the center than at the ends; angular coupling members mounted on the bars on each side of the center of the track; a series of hooked rods adjustably secured to one set of angular coupling members and engaging one rail, the other set of rods being adjustably connected to the other set of angular members and engaging the other rail.

13. The combination of a ballast having an inclined surface at each side; wedges mounted on the inclined surfaces; rails carried by the wedges; a series of transverse bars in the ballast and having anchor plates, also mounted in the ballast; coupling members on each side of the center of the track; rods connecting the coupling members with 110 the outer base flanges of the rails; and anchor rods diagonally arranged within the ballast beyond the track and having adjustable hooked connections engaging the inner base flange of the rails.

14. The combination of a ballast having an inclined surface at each side; wedges mounted on the ballast; rails carried by the wedges; anchors located within the ballast; rods connecting the anchors with each base 125 flange of each rail; means for independently adjusting the rods; the said adjusting means being located above the ballast.

15. The combination of a ballast having an inclined surface at each side; a coating of water-proofing material applied to said surface; a series of wedges mounted on the 5 inclined surfaces; rails carried by the wedges; and a series of transverse anchors embedded in the ballast and connected to the rails independently of the wedges.

16. The combination of a ballast having a 10 horizontal central surface and an inclined surface at each side of the center, the upper surface of the ballast being covered with water-proofing material; a series of wedges mounted on each inclined portion of the ballast; a series of transverse anchors located 15 in the ballast; and means connecting the rails with the ballast so that the lateral strains will be taken directly by the ballast through the anchors, while the weight will 20 be taken by the ballast through the wedges.

17. The combination of a ballast; means 25 for supporting the rails on the ballast; a series of transverse bars embedded in the ballast and having anchor plates at each side, also embedded in the ballast; and means

for coupling the bars to the rails, the anchor plates extending under the means for supporting the rails.

18. The combination of a ballast having an inclined surface at each side; a series of 30 wedges mounted on the inclined surfaces of the ballast; rails supported by the wedges; a series of transverse anchor bars embedded in the ballast and having anchors at each end, the center portion of the bars being 35 nearer the upper surface of the ballast than the end portions thereof, each bar being bent to form a shoulder.

19. The combination of a ballast having an inclined surface at each side; a series of 40 wedges; rails mounted on the wedges; a series of transverse bars forming anchors and embedded in the ballast; coupling members mounted on the bars; hooked rods engaging the outer base flange of each rail and 45 extending through the coupling members; and insulating material located between the rods and the coupling members.

In witness whereof I affix my signature.
RUFUS WAPLES.
